UNITED STATES PATENT OFFICE.

FRANCIS KEIL, OF NEW YORK, N. Y.

LATCH.

SPECIFICATION forming part of Letters Patent No. 340,323, dated April 20, 1886.

Application filed January 18, 1886. Serial No. 188,997. (Model.)

To all whom it may concern:

Be it known that I, FRANCIS KEIL, of the city, county, and State of New York, have invented a new and Improved Latch, of which 5 the following is a full, clear, and exact description.

The object of this invention is to improve the construction of that class of latches known as "night" or "safety" latches.

10 The invention consists in a novel construction and arrangement of locking devices in connection with the dog by which the bolt is retracted by means of a key from the outside of a door. The invention further consists in 15 a peculiar form of key for the outside locking mechanism. The invention also consists in details of construction and arrangement of parts, as will be hereinafter more specifically set forth.

20 Reference is to be had to the accompanying drawings, forming part of this specification, in which similar letters of reference indicate corresponding parts in all the figures.

Figure 1 is a plan view of the back of the 25 latch with the back plate and outside locking mechanism removed, the bolt being shown held in the inner position. Fig. 2 is the same view with the parts as when the bolt is in the outer position, the bolt being shown in dotted lines, the dog for retracting the bolt from the 30 outside being in place, and parts being in section on the line *x x*, Fig. 3. Fig. 3 is a central longitudinal sectional view of the latch on the line *y y*, Fig. 2. Fig. 4 is a transverse 35 sectional view on the line *z z*, Figs. 3 and 7. Fig. 5 is a transverse sectional view on the line *u u*, Fig. 7, showing the key inserted and the tumblers withdrawn. Fig. 6 is a cross-section 40 on the line *v v*, Fig. 5. Fig. 7 is a sectional 45 plan view on the line *w w*, Fig. 4. Fig. 8 is a plan view of the housing. Fig. 9 is a plan view of one of the tumblers. Fig. 10 is a side view of the key.

The bolt A, held to slide in the casing B, is 45 kept normally in the outer position by the spring C, and can be moved to the inner position by the knob D. E is the back plate of the casing, held in place by a screw entering the socket h. The bolt A is recessed at its front 50 side at *a*, and its inner end is forked to form the prongs *b b*. Lugs *c c* extend from the ends of these prongs to the plane of the front side

of the bolt. Lugs *d d* project from the inner side of the back E to the prongs *b b*, and lugs *e e* on the front of the casing hold the bolt 55 against lateral movement. Back of the head *f* of the bolt is an aperture, *g*. A locking dog, F, is pivoted to the bolt A and located between said bolt and casing in the recess *a* by a stud, *i*, fitting loosely in the aperture *g*. 60 From the free end of this dog a stem, *j*, or handle projects through an L-shaped slot, G, in the front of the casing, upon which stem the manipulating-knob D is secured, (or the stem may be formed on the knob and riveted to the 65 dog.) On that side of the dog F adjacent to the short arm of the slot G is a hook-lug, *k*, and on the front of the casing, in position to be engaged by the hook *k*, is a lug, *l*, having its engaging end beveled approximately on a circumferential line from the axis of stud *i*. 70 Forward of the lug *l* is a stud, *m*, around which is passed the coil of the spring C, one end of which spring bears against a lug, *o*, and its other end against the stem *i* of dog F. By 75 this construction and arrangement of the parts the bolt can be slid inward, and is free to be thrown outward by the spring, the tension of the spring holding the hook *k* away from the lug *l*. When it is desired to hold the bolt in 80 the inner position, the stem *j*, after being moved to the inner position, is shifted sideways into the short arm of the slot G, whereby the hook *k* is engaged with the lug *l*, and is held engaged by the spring holding the dog 85 F and bolt A.

On the inner side of the face of the casing B, between the prongs *b b*, is the stud *n*. A tubular housing, H, projects from the back plate, E, the axis of which housing coincides 90 with that of the stud *n*. At the outer end of the housing H is an internal annular flange, *h'*, and at diametrically opposite points of the interior of the housing are formed the longitudinal grooves *p*.

95 On the stud *n* is mounted the retracting-dog K, the arms *q* of which engage the lugs *c c* of bolt A. For operating the dog K and locking it against being turned, I provide the mechanism now to be described. The barrel L, attached to or formed integral with the dog K, extends outward therefrom into the bore of the housing H, which it fits snugly. The barrel L is slotted diametrically at M, the width 100

of the slot being the same as that of the groove p . The slot M extends from the dog K about two-thirds the length of the barrel. From the slot M the slit r extends to the end of the barrel, said slit being in line with and central of the slot M . Two extensions of said slit or rabbits r' are formed in the side parts of the barrel at the opposite corners of the slit r , which extend to the sides of slot M . In the slot M on the pins s and t are pivoted the three tumblers, N , O , and N' . The central tumbler, O , pivoted near the bottom of the slot M on the pin s , is of a width equal to the diameter of barrel L , and is provided in its free end with the recess u , forming the two points v and v' , the points being toward the outer end of the barrel. The tumblers N and N' are pivoted on the pin t near the upper end of the slot M , the pin passing through the apertures w of the tumblers. The spring x , through the central coil of which the pivot-pin t passes, is held thereby in the recess u of the tumbler O , and the ends of this spring bear, respectively, upon opposite ends of the inwardly extending arms n' of the tumblers N and N' , forcing the points n^2 and n^2 of the tumblers into the grooves p of the housing. The tumbler O is free to turn upon its pivot by gravity, so that if the latch is used either as a right or left hand latch one of its points v or v' will engage a groove, p . The tumblers N and N' are each cut away or shaped to form on the side opposite the point n^2 the shoulder n^3 , the position of which will be varied for different latches. The points n^2 of the tumblers N and N' and one of the points of the tumbler O are normally engaged with the grooves p of the housing H , and hold the barrel L from being turned without a suitable key. For turning the barrel and withdrawing the bolt, I provide the key shown in Fig. 10. This key corresponds in cross-section with the slit r and r' in the barrel L , and consists of a flat portion or body, R , and two oppositely-extending marginal flanges, S . As shown, one of the flanges S is slightly cut back from the entering end of the key, to form a shoulder, p' , which is positioned to engage the shoulder n^3 of the tumbler N' . The outer flange S is left with its shoulder p^2 flush with the end of the key. The part R of the key is recessed at p^3 to form the points q' , which are preferably rounded on their outer edges for engagement with the points v and v' of the tumbler O . The flanges S can be cut away to position the points p' and p^2 at any point required by the position of the shoulders n^3 of the tumblers N and N' . The recess p^3 is made of a depth so that the pivot-pin t shall come to bear in the base of said recess when the tumblers are fully withdrawn into the barrel, and so prevent further endwise movement of the key, and consequent throwing of the tumblers too far. When the key Q is entered into the slit r , one of the points q' will engage one of the points v and v' of the tumbler O . A further endwise movement of the key will engage the shoulders p' and p^2 with the shoulders n^3 of tum-

blers N and N' , and will withdraw all the tumblers into the barrel L , when the barrel can be turned and the bolt A moved to the inner position. 70

I do not limit myself to the arrangement shown of the tumblers, nor to the position of their operating-shoulders, nor to the position of the shoulders on the key, as the same may 75 be differently arranged within the scope of my invention.

Having thus described my invention, what I claim as new, and desire to secure by Letters Patent, is— 80

1. The combination, with a latch-casing provided with an L-shaped slot and a sliding spring-actuated bolt, of a dog pivoted at one end to said bolt, and provided at its free end with a stem extending through said L-slot in 85 the casing, and with a hook-lug adjacent to said stem, and of a lug on the casing adjacent to said L-slot, substantially as shown and described.

2. The combination, with the spring-actuated bolt of a night latch, an armed dog for retracting said bolt, and a grooved housing on the latch-casing, of a slotted barrel integral with said dog, spring-actuated tumblers pivoted in said barrel, and a gravity-tumbler also 95 pivoted in said barrel, substantially as shown and described.

3. The combination, with a grooved housing, a barrel fitted to turn therein, and a gravity-tumbler pivoted in said barrel, of two 100 tumblers pivoted in said barrel at the sides of and opposite to said gravity-tumblers, and each provided with arms extending toward the pivot of the gravity-tumbler, and a spring acting on one arm of each of the said two-armed 105 tumblers, substantially as shown and described.

4. The combination, with a grooved housing, of a diametrically-slotted barrel formed integrally with the retracting-dog of the latch and held to turn in the housing, and tumblers 110 pivoted in the said barrel and normally engaging the grooves of the housing, substantially as shown and described.

5. The combination, with a retracting-dog and a barrel projecting from the same, provided with tumblers normally engaging grooves in the housing of the barrel, and provided with operating-shoulders, substantially as set forth, of a key having shouldered flanges to engage the shoulders of said tumblers, substantially as shown and described, whereby an endwise movement of said key will withdraw the tumblers from engagement with the housing. 115 120

6. A barrel projecting from the retracting-dog of a latch-bolt slotted diametrically for carrying locking-tumblers, and provided with a diametrical slit extending from the slot carrying the tumblers to its outer end, and said slot having two side extensions, substantially as 125 130 shown and described.

7. The combination, with a slotted barrel carrying tumblers and provided with a slit having side extensions, substantially as set

forth, of a key having a flat main portion or body and edge flanges, and adapted to fit in said slit of the barrel, substantially as shown and described.

8. The combination, with a slotted barrel provided with shouldered tumblers and a three-part slit, as set forth, of a key having a flat main portion or body and oppositely-arranged side flanges, said flanges being cut away to form shoulders, and said main body being recessed at its operating end, substantially as shown and described.

9. A key formed with a flat main portion or body and with side flanges, substantially as shown and described.

10. A key formed with a flat main portion or body, and with oppositely arranged side flanges, and said main body and flanges cut away to form engaging shoulders, substantially as shown and described.

11. The combination, with a diametrically-slotted barrel, of a tumbler pivoted at one end centrally in said barrel, and provided at its free end at each corner with a point extending in lines parallel with the longitudinal axis of the dog, substantially as shown and described.

12. The combination, with a slotted barrel, of two oppositely arranged tumblers pivoted therein, each provided at one end with an en-

gaging-point and an operating-shoulder, and at the other end with two opposite arms, and of a spring acting on one arm of each tumbler, substantially as shown and described.

13. The combination, with a grooved housing and a slotted barrel held therein, of the tumbler O, having the points v v', the pivot-pin s, the tumblers N N', having each the arms n', point n², and shoulder n³, the pin t, and the spring x, substantially as shown and described.

14. The combination, with the casing B, having stud n, and the bolt A, of the dog K, mounted on said stud and carrying the slotted barrel L, the housing H, carried by the back plate and having the flange h', the tumblers N O N', pivoted in said barrel, and the spring x, substantially as shown and described.

15. The combination, with the bolt, the retracting-dog, the barrel L, carrying the locking-tumblers, and provided with the slit r r', of the housing H, having the grooves p and flange h', substantially as shown and described.
